CLAIM

The ornamental design for a highway median strip divider, as shown and described.

DESCRIPTION

FIG. 1 is an enlarged perspective view of a section of the highway median strip divider shown in FIG. 3, showing my new design;

FIG. 2 is a top plan view of the highway median strip divider,

FIG. 3 is a side elevational view thereof, the other side being identical, and

FIG. 4 is an end elevational view thereof, the other end being identical.
